UNITED STATES PATENT OFFICE.

HARRY L. OGG, OF NEWTON, IOWA, ASSIGNOR TO AUTOMATIC ELECTRIC WASHER COMPANY, OF NEWTON, IOWA.

SUPPORTING-FRAME FOR WASHING-MACHINES.

1,226,988.

Specification of Letters Patent. Patented May 22, 1917.

Application filed May 6, 1916. Serial No. 95,888.

To all whom it may concern:

Be it known that I, HARRY L. OGG, a citizen of the United States, residing at Newton, in the county of Jasper and State of Iowa, have invented certain new and useful Improvements in Supporting-Frames for Washing-Machines, of which the following is a specification.

This invention has as its object to provide a novel frame structure for supporting motor operated washing machines and more particularly that type embodying two tubs and it is one aim of the invention to provide a frame structure which will be light in weight and which will yet be so constructed as to firmly support the tubs and the washing mechanism and also a wringer mechanism in such manner that the structure as a whole will occupy a minimum amount of space when not in use.

Another aim of the invention is to provide in a supporting frame structure of the class described, a supplemental supporting frame hingedly connected with the main supporting frame structure and capable of being swung up to position to support one or more tubs, baskets, or other receptacles to receive the clothes after passage between the wringer rolls.

Another aim of the invention is to provide a supporting frame structure of the class described, so constructed as to support the motor and power transmission gearing for operating the washing and wringing mechanisms below the tubs and consequently out of the way and in such position that there will be no likelihood of the operator's clothing catching in the gearing.

In the accompanying drawings:

Figure 1 is a front elevation of the supporting frame structure embodying the present invention.

Fig. 2 is a perspective view thereof.

Fig. 3 is a perspective view of one corner piece of the supporting frame structure.

Fig. 4 is a perspective view of one of the hinged members for the supplemental frame. Fig. 5 is a side elevation illustrating one of the supports for the supplemental frame.

In the drawings the supporting legs or standards of the frame structure are indicated by the numeral 1 and these standards are four in number and are located one at each corner of the structure, the standards being tubular in form and provided at their

lower ends with any suitable type of casters indicated by the numeral 2. Each standard supports at its upper end a corner piece which includes a tubular socket 3 fitted to the upper end of the respective standard 60 and secured in place by means of a set screw 4 threaded through a boss 5 formed exteriorly upon the said socket. The sockets 3 of the corner pieces are reduced interiorly at their upper ends to form shoulders 6 65 against which the upper ends of the standards 1 seat in the manner shown in Fig. 1 of the drawings. The body of each corner piece comprises right angularly extending portions each having a horizontal wing 7 70 and a vertical wing 8, the socket 3 being integral at its upper end with the wings 7 at their point of juncture. The top of the frame structure includes side bars 9 and 10 and end bars 11 and by reference to Fig. 2 75 of the drawings it will be observed that the bars 9, 10 and 11 are of angle iron and that each includes a horizontal wing 12 and a vertical wing 13. The bars are disposed at their ends upon the horizontal wings 7 of the 80 corner pieces and with their vertical wings 13 resting against the vertical wings 8 of the said corner pieces and are secured after being thus positioned by means of rivets or other suitable fastening devices 14. In order that the sides 9 and 10 may be relatively braced and in order that two tubs may be supported upon the top of the frame structure, a supporting board 15 is disposed at its ends upon the horizontal flanges 12 of 90 the side members 9 and 10 and secured in place by rivets or bolts as indicated at 16. The tubs are shown in dotted lines in Fig. 1 of the drawings and indicated in general by the reference character T, and in order that the tubs may be secured in place when disposed upon the top of the frame structure, one vertical wing 8 of each corner piece is formed with an ear which is integral with the upper edge of the said wing and which 95 extends laterally outwardly as at 17 and thence upwardly as at 18 and is provided in its upstanding portion 18 with an opening 19 for the passage of a securing bolt or rivet 20. It will be observed that the ears upon 105 the corner pieces are located at the extreme ends of the frame and that the tubs are disposed with their bottoms resting upon the upper edges of the flanges 13 of the end bars 11 and the flanges 13 of the side bars 9 and 110

10, and with their bottoms resting also upon the supporting board 15. The distance between the ears upon the corner pieces at each end of the frame is less than the diameter 5 of the bottom of the respective tub and consequently the tub will seat at its bottom upon the portions 17 of the ears and the portions 18 of the ears will upstand beside the walls of the tubs and brace the tubs 15 against movement outwardly upon the top of the frame in the direction of the ends thereof. In order to similarly brace the tubs against movement inwardly upon the top of the frame, and to secure the tubs in place, securing ears 21 are fixed upon the upper surface of the supporting board 15 at each lateral edge thereof and are provided with apertured upstanding portions 22 through which bolts may be passed and secured to the tubs at their lower ends. 20

In order to further brace the standards 1 with relation to each other and to afford support for the motor and transmission gearing for supplying power to the washing 25 and wringing mechanisms, angle bars 23 are secured at their ends as at 24 to the standards 1 at each side of the structure and extend horizontally beneath the side bars 9 and 10 heretofore described, and angle bars 30 25 are secured at their ends as at 26 to the ends of the bars 23 at the ends of the frame structure and extend horizontally beneath the end bars 11. Thus the structure is provided with a rectangular under frame 35 which, as will be now explained, serves to support the motor and transmission gearing and also to brace the standards 1 with relation to each other. In order that the bars 23 may be prevented from sagging at their 40 intermediate portions, hangers 27 are secured at their upper ends to the intermediate portions of the side bars 9 and 10 and at their lower ends as at 28 to the intermediate portions of the bars 23 and diagonal 45 brace bars 29 are secured at their lower ends as at 30 to the said bars 23 near one end of the frame 1 and at their upper ends as at 31 to the horizontal wings 7 of the adjacent corner pieces. Secured at its ends to 50 the intermediate portions of the bars 23 is an intermediate frame bar 32 and disposed at their ends upon the bar 32 and one of the bars 25, are spaced supporting boards 33 upon which the motor and transmission 55 gearing indicated in general by the reference letter M in Fig. 1 of the drawings, is supported. The bars 32 and 25 are relatively braced by a cross bar 34 secured at its ends to the first mentioned bars and extending therebetween and between the adjacent edges of the supporting boards 33. 60

The supplemental frame heretofore referred to comprises side members 35, a connecting side bar 36 and an intermediate connecting and bracing bar 37. Hinged mem-

bers of the form shown in Fig. 4 of the drawings are provided for hingedly connecting the supplemental frame with the main frame structure and each of these said members comprises an attaching portion indicated by the numeral 38 and provided with an upstanding right angularly positioned hinge ear 39, apertured as at 40 for the passage of rivets or other suitable elements 41 which pass also through the side members 35 of the supplemental frame and serve to hingedly connect the said supplemental frame to the members 38, as shown in Fig. 2 of the drawings. The body portion 38 is provided with spaced lugs 42 and 70 below the lugs with openings 43 and in securing the hinge members to the main frame structure, the said body portions of the members are disposed against the outer faces of the upstanding flanges 8 of the corner pieces 80 which support the side bar 10 of the main frame structure with the lugs 42 resting against the upper edge of the said upstanding wing 8 and rivets or other suitable fastening devices 44 are secured through the 85 openings 43, the said wings 8 and the upstanding wings of the side bar 10. When in lowered position the supplemental frame extends down beside the main frame structure and in order that the supplemental 90 frame may be supported in raised position, bars 45 are pivoted at their upper ends as at 46 to the outer ends of the side members 35 of the said supplemental frame and at their lower ends are provided in their under 95 edges with notches 47 designed to engage pins 48 which are secured in the rear one of the standards 1.

It will be understood from the foregoing description of the invention, that the upper 105 ends of the legs 1 may be readily removed from the sockets 3 by loosening the set screws 4 and that the lower portion of the frame may be separated from the supporting legs by removal of the bolts 24. It will 110 also be understood that when the washer mechanism is to be driven by a belt or other gearing from some source of power not directly supported upon the frame, the casters 2 may be omitted and also it will probably 115 be found desirable to substitute for the braces 45, suitable angle iron legs which are designed to rest upon the surface upon which the frame is disposed.

Having thus described the invention, what 120 is claimed as new is:

1. In a supporting frame structure of the class described, supporting standards, corner pieces mounted at the upper ends of the standards and each having a horizontal 125 wing and an upstanding wing, side and end frame members disposed and secured at their ends within the angles between the said wings of the corner pieces, a supporting board extending between the front and rear 130

- members of the top of the frame and supported thereby, and tub securing elements upon the said board and upon each of the said corner pieces.
5. 2. In a supporting frame structure of the class described, a corner piece including a horizontally disposed wing and an upstanding wing, and a socket member projecting downwardly from the underside of
- 10 the horizontal wing and designed to receive the end of a supporting leg, the upstanding wing being formed at its upper edge with an integral extension bent to extend laterally outwardly from the plane of the
- 15 wing to form a horizontally disposed supporting portion and thence bent upwardly to form a securing ear upstanding from the said supporting portion and having an opening for the passage of a securing element,
- 20 the said supporting portion occupying substantially the same plane as the upper edge of the upstanding wing of the said corner piece.
3. In a supporting frame structure of the class described, a corner piece including 25 relatively angularly extending portions having integrally connected horizontal supporting wings and integrally connected upstanding securing wings each provided with an opening for the passage of a securing element, a socket member projecting downwardly from the first-mentioned wings at their juncture and designed to receive the end of a supporting leg, and an extension integral with the upper edge of one of the 30 upstanding wings bent to extend laterally outwardly from the plane thereof to form a supporting portion parallel to and located above the plane of the corresponding horizontal wing and thence bent upwardly to 35 form an upstanding securing ear having an aperture for the passage of a securing element.

In testimony whereof I affix my signature.

HARRY L. OGG. [L.S.]
